Attorney

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed September 30, 1922. Serial No. 591,456.

To all whom it may concern:

Be it known that I, JESSE A. B. SMITH, a citizen of the United States, residing in Stamford, in the county of Fairfield, and State of Connecticut, have invented certain new and useful Improvements in Type-writing Machines, of which the following is a specification.

This invention relates to typewriters, and 10 more particularly to typewriters wherein provision is made for positioning a plurality of work-sheets in the machine, side by side, independently of each other.

A feature of the invention is the provision of two collating tables above the platen at the front thereof for positioning work-sheets, side by side, with clamping means on one of the collating tables for holding a sheet in position upon it while the feed- 20 rollers are thrown off to permit the other sheet to be properly positioned in the machine.

Another feature of the invention is the provision of separate means for guiding two 25 work-sheets through the machine, side by side, in combination with tally-strip mechanism for feeding the tally-strip around the platen beneath the inner margins of both sheets to receive certain of the items typed 30 on each of the sheets.

Other features and advantages will hereinafter appear.

In the accompanying drawings,

Figure 1 is a front elevation of the platen-frame of an Underwood standard typewriter having the improvements of the present invention combined therewith.

Figure 2 is a vertical section taken beyond the right end of the platen and looking 40 toward the left in Figure 1.

A platen-frame 10 supports a platen-shaft 11 which carries a platen 12, and is revolute by the usual line-spacing mechanism, not shown, operating through a ratchet-wheel 13, or by a knob 14. The usual feed-rollers 15 co-operate with the platen to control the paper and are movable to effective and ineffective positions by the usual paper-release handle 16 and its connected train of 45 mechanism comprising a shaft 17, crank-arm 18, link 19, crank-arm 20, cam-shaft 21 and the downwardly-extending tails 22 of the levers 23 which carry the feed-rollers.

A bracket 24 is secured upon the platen-frame 10 and supports collating tables 25

and 26, side by side, above the platen at the front thereof. The table 25 has lateral edge gages 27 and 28, and the table 26 has lateral edge gages 29 and 30 for assisting in positioning the work-sheets in the machine. A 60 plate 31 fixed upon the outer face of the edge gage 27 has outwardly-bent ears 32 with holes therein which serve as bearings for a shaft 33 having a crank-handle 34 and a clamping arm 35 fixed upon it. A coil 65 spring 36 is connected to pins 37 and 38 on the clamping arm 35 and one of the ears 32, respectively, the arrangement being such that the spring will cross the center of the shaft 33 when the clamping arm is moved 70 in either direction between effective and ineffective positions, and will therefore serve to hold the clamping arm in either of these positions.

Tally-strip mechanism comprising reels 75 39 and 40 is provided for feeding a tally-strip 41 around the platen in a position to underlie a portion of each of the sheets on the collating tables 25 and 26, so that it will receive impressions of the items typed on 80 these portions of the sheets. This tally-strip mechanism is identical with that disclosed in the patent to Hart, No. 1,281,160, and will not, therefore, be described further.

Public utility companies, such as electric 85 light companies, which operate over a large territory and have branches at different localities, sometimes maintain two different kinds of ledgers, one known as a location ledger which always stays at a particular 90 location, and the other known as a customer's ledger which follows the customer as he moves from place to place in the territory served by the company. At the time a bill is rendered to a customer, entries are made in appropriately headed columns of a location ledger-sheet indicating 95 the date, meter readings, consumption, several items of charge and the total amount of the bill. At the same time the date and total amount of the bill are entered in date and debit columns at the left of the customer's ledger-sheet.

The machine disclosed is used for doing this work as follows: with the feed-rollers thrown off, the location ledger-sheet 42 is inserted at the left end of the platen, adjusted to the line of writing and clamped against the collating table 25. The customer's ledger-sheet 43 is then inserted at the right end of the platen and ad- 100 105 110

justed to the line of writing. The feed-rollers are then moved to effective position, the clamp is withdrawn, a single line of items is typed including the items above 5 enumerated on the location ledger-sheet, and the date and total amount of the bill on the customer's ledger-sheet, and the work is removed from the machine by the turning of the platen through a knob 14 in the usual 10 way or the feed-rollers may be cast off and both sheets drawn out at the front of the platen. The tally-strip lies in position to receive the item of consumption and the various items of charge including the total 15 amount of the bill from the location ledger-sheet, and extends to the right far enough to receive the date and the total amount of the bill from the customer's ledger-sheet, and is usually line-spaced after the single line entry 20 25 is completed on both sheets. The total amount of the bill, therefore, appears on the tally-strip as it has been written on each of the ledger-sheets. It will be seen that the tally-strip affords a convenient check to ascertain whether or not the same amount has 30 been written upon the two ledger-sheets after they have been separated.

The above example should, of course, be regarded merely as illustrative of the use of 35 the invention, and not as defining the scope of the use to which the invention may be put.

It will be seen that the collating tables 25 and 26 with their turned-up edges 27, 28 35 and 29, 30, respectively, comprise a pair of paper gages; that the width between the two turned-up edges is approximately the width of a work-sheet; that by laying the work-sheets within the gages, each sheet squares 40 itself relative to the platen and relieves the operator of that much responsibility; that the operator is only required to raise or lower the sheet within its gage as a final adjustment to align the last printed entry 45 thereon to the wing-scales for a line-spacing position; that the feed-rollers are grouped into two series, one series for each work-sheet; that both series of rollers are released or set in unison by a single key-lever; and 50 that the turning of the finger-wheels will run out both work-sheets in unison, over the stationary tally-strip after the typing operation.

Variations may be resorted to within the 55 scope of the invention, and portions of the improvements may be used without others.

Having thus described my invention, I claim:

1. In a typewriting machine, a platen, 60 means for positively positioning individually a pair of related work-sheets side by side in non-overlapping relation, said means comprising collating tables arranged side by side and independent of each other and 65 above the platen at the front thereof, the

lateral edges of each table provided with edge gages, the structures of the respective adjacent edge gages being independent of each other, paper-feeding means to feed both work-sheets around the platen in unison, and tally-strip feeding mechanism to feed a tally-strip around the platen independently thereof and in position to underlie the adjoining edges of both work-sheets. 70

2. In a typewriting machine, a platen, 75 separate pairs of lateral edge gages in front of and above the platen, the structures of the respective adjacent lateral edge gages being independent of each other, to independently and positively position a pair of 80 related work-sheets at predetermined alignments to the platen in non-overlapping relation, a series of paper-feeding rollers for each work-sheet, and key-actuated means to render both series of feed-rollers ineffective 85 during the adjustment of both work-sheets and render said rollers effective to feed both work-sheets in unison after the adjustment thereof is completed.

3. In a typewriting machine, a platen, 90 paper-feeding rollers to feed a pair of related work-sheets side by side in non-overlapping relation around the platen, key-actuated means to render the feed-rollers effective or ineffective to feed the work-sheets, work-sheet gaging means above and 95 in front of the platen, said gaging means comprising separate pairs of lateral edge gages, the structures of which are independent of each other, to positively align 100 each work-sheet at a predetermined position on the platen when the feed-rollers are ineffective, and a tally-strip mechanism arranged to feed a tally web under the adjoining margins of both work-sheets, to receive 105 fragmentary entries from each work-sheet.

4. In a typewriting machine, a platen, 110 feed-rollers arranged to co-operate with the platen to feed work-sheets around it, and movable to ineffective positions, a plurality 115 of tables arranged side by side above the platen, at the front thereof, each of the tables having right and left lateral sheet gages, and a clamp on one of the tables for clamping a work-sheet against it while the feed-rollers are in ineffective positions, to permit the adjustment of a work-sheet in the machine upon the other table.

5. In a typewriting machine, a platen, 120 paper-feeding rollers co-operating with the platen to feed a pair of work-sheets in non-overlapping relation, and paper-gaging means to positively position each work-sheet at predetermined printing positions on the platen, comprising a pair of lateral edge 125 gages for each work-sheet, the structures of the adjacent edge gages being independent of each other, and placed above and in front of the platen.

6. In a typewriting machine, a platen, 130

paper feed-rollers co-operating with the platen to feed a pair of related work-sheets simultaneously, means for positively gaging each work-sheet to a predetermined printing position in a non-overlapping relation, comprising a pair of edge gages for each sheet, and a tally-strip mechanism to feed a tally-strip under the adjoining margins of both work-sheets.

10 7. In a typewriting machine, a unitary platen, rollers co-operating with the platen to feed a plurality of work-sheets around the platen, side by side, a plurality of collating tables, each having lateral edge gages for guiding work-sheets around the platen, side by side, and tally-strip mechanism for feeding a tally-strip around the platen beneath adjacent margins of the work-sheets.

15 8. In a typewriting machine, a platen, a

tally-strip mechanism arranged to independently feed a continuous strip around the platen under the margins of adjacent side-by-side work-sheets, paper feed-rollers to feed the work-sheets over the tally-strip, means to render said rollers effective or ineffective at will, work-sheet gaging means above and at the front of the platen, said gaging means comprising gages at each side of each sheet, to positively square both sheets to the platen in non-overlapping relation while the rollers are cast off, line-spacing means to feed both sheets in unison, over the tally-strip, when the rollers are effective, and means for retaining one of the sheets in adjusted position when the rollers are in their ineffective position and the other sheet is being adjusted.

JESSE A. B. SMITH.
